United States Patent Office

Des. 183,879
Patented Nov. 11, 1958

183,879

COMBINED METER AND SWITCH PANEL

Cherry L. Emerson, Jr., Duxbury, Mass., assignor to
Callaghan Hession Corporation, Boston, Mass., a cor-
poration of Massachusetts

Application January 30, 1956, Serial No. 39,967

Term of patent 14 years

(Cl. D26—13)

FIG. 1

Fig. 1 is a front elevational view of a combined meter and switch panel, showing my new design;

Fig. 2 is a side elevational view;

Fig. 3 is an opposite side elevational view; and
Fig. 4 is a bottom plan view thereof.

Legible matter is shown in zigzag lines for illustrative purposes in Fig. 1.

I claim:

The ornamental design for a combined meter and switch panel, substantially as shown and described.
